(57) **CLAIM**

(22) Filed: **Jan. 28, 2010**

The ornamental design for the toy rocket ship convertible into a table and chair set, as shown and described.

(51) **LOC (9) Cl.** **21-01**

DESCRIPTION

(52) **U.S. Cl.** **D21/452**; D6/337

FIG. 1 is a front perspective view of a toy rocket ship convertible into a table and chair set of this invention;

(58) **Field of Classification Search** D6/337,

FIG. 2 is a front view of the toy rocket ship configuration of this invention;

D6/351, 358; D21/441-452; 446/230-231;
297/157.1, 158.3

FIG. 3 is a right-side view of the toy rocket ship of this invention;

See application file for complete search history.

FIG. 4 is a rear view of the toy rocket ship of this invention;

(56) **References Cited**

FIG. 5 is a left-side view of the toy rocket ship of this invention;
